UNITED STATES PATENT OFFICE.

FRANK C. DE REAMER, OF BRIDGEPORT, CONNECTICUT, ASSIGNOR TO GENERAL ELECTRIC COMPANY, A CORPORATION OF NEW YORK.

LIGHTING FIXTURE.

Application filed November 11, 1922. Serial No. 600,206.

To all whom it may concern:

Be it known that I, FRANK C. DE REAMER, a citizen of the United States, residing at Bridgeport, in the county of Fairfield, State 5 of Connecticut, have invented certain new and useful Improvements in Lighting Fixtures, of which the following is a specification.

The present invention relates to detachable fixtures of the type in which certain of the parts are permanently wired either in the side wall or ceiling of a room which is to be lighted while the other parts which are also permanently wired are arranged to 15 be quickly detached from said wall or ceiling parts. The detachable parts are provided with a canopy which carries the lamp supporting bracket.

In mounting and taking down canopies of 20 this character there is liability of marring or scratching the finish around the permanently installed parts, as for example, the wall paper, and the object of the present invention is to provide a simple, effective 25 means for preventing such injury.

For a consideration of what I believe to be novel and my invention, attention is directed to the accompanying description and the claims appended thereto.

30 In the drawing which is illustrative of my invention, Fig. 1 is a view in elevation of a canopy which is partly broken away to show the inside parts; Fig. 2 is a view in side elevation partially broken away, showing the position of the canopy just before being finally seated; Fig. 3 is a similar view but showing the canopy in its seated position; Fig. 4 is a perspective view of the attachment plug and the member which carries it and also supports the canopy, and Fig. 5 is a front elevation of a finishing or surface plate.

Referring to Fig. 2, 5 indicates the side wall or ceiling, designated hereafter as a 45 wall, and 6 a metal outlet box suitably supported therein. Located in the box is a receptacle 7 made of insulating material which is of usual construction and contains the necessary contacts and binding posts 50 for the supply circuit wires. Resting on the surface of the wall 5 is a face or cover plate 8 of any suitable configuration which contains three slots that are arranged to receive the three load supporting hooks 9, 55 10 and 11, Fig. 4 formed on the supporting

box-like member 12. The plate 8 is covered by a finishing plate 13, usually of brass, which is provided with slots 9^a, 10^a and 11^a, that register with those in the face plate and through which the supporting hooks 60 are free to pass. Preferably, but not necessarily, the receptacle which is made of insulating material, is secured by screws to the face plate so that the electrical contacts therein will be properly aligned to receive 65 the cooperating blades of the attachment plug. The receptacle is provided with a projection 7^a which extends outwardly and terminates flush with the finishing plate 13 and contains slots 7^b of suitable size and 70 shape to receive the blades of the attachment plug.

The member 12 comprises a metallic box having a front wall, two sides and two ends, the two sides and lower end being provided with said hooks 9, 10 and 11. Inside of the box and capable of limited movement therein, is a rectangular attachment plug 14 having two contact blades 15 which are wired to the socket on the lamp supporting bracket and are adapted to engage stationary contacts in the receptacle and complete the electrical circuit. The attachment plug is retained in the box member 12 by means of a pin 14^a and a screw 14^b located 85 at diagonally opposite corners. On the lower end of the box is a spring-pressed locking device 16 which fits into the lower slot after the hook 11 is in place and prevents the accidental displacement thereof 90 but which is not material to an understanding of the present invention.

Riveted or otherwise firmly secured to the box is a holder 17 for the canopy 18. This holder is slightly resilient in order to hold 95 the canopy against the wall and also to compensate for inaccuracies in the setting of the parts or in the construction of the canopy or both. In the form shown the holder comprises a U-shaped piece, the legs of which straddle the box and at their lower ends are riveted or otherwise secured to the sides of the box. On the bridge piece of said U-shaped piece is formed a tongue 19, the outer end of which is bent backwardly 100 and away from the finishing plate to act as a guide in slipping the canopy in place. On the back of the canopy and secured at its ends thereto is a horizontal support or strap 105 20 which when the canopy is mounted in 110

place is supported against downward movement by the upper wall of the box and against outward movement away from the wall by said holder.

- 5 In order to prevent the relatively sharp edges of the canopy from scratching or marring the wall as it is being slipped into place, a special arrangement is provided which holds the canopy away from the wall by a
 10 slight space while it is being pushed downward into register with its final position. This arrangement comprises a means which positively engages the strap and pushes it and the canopy outwardly and away from the wall until the final position of the canopy is reached. As here illustrated it comprises a U-shaped member 21, the legs of which straddle the box and are either secured at their lower ends directly to the box or indirectly to it through the legs of the holder 17 to which the legs of the member are riveted, the latter being the simpler arrangement. Backward movement of the member 21 or that toward the finishing plate is limited by
 25 the stops 22 which are formed integral with the box. On the bridge part of the member 21 is a tongue 23 the outer end of which is beveled or inclined toward the brass finishing plate 18. By the arrangement described
 30 the two tongues 19 and 23 form a V-shaped guide and both act as guiding means to direct the strap on the canopy into its proper place. At the bottom of the inclined portion of the tongue 23 is formed a small projection
 35 24 which performs three functions. First, it pushes the strap and the canopy outwardly away from the wall as the latter is moved downwardly by a sufficient amount to prevent the edges of the canopy from rubbing
 40 on the wall paper surrounding the face or finishing plate; second, it acts as a friction lock to prevent the strap from being accidentally dislodged from place by an upward thrust, and third, it acts to push the strap
 45 and canopy away from the wall while the latter is being removed by an upward movement. Fig. 2 illustrates the position of the parts as the canopy is being moved into place, and Fig. 3 illustrates the canopy after
 50 it has been seated. From this latter figure it will be seen that the projection 24 is located just above the strap and that the legs of the resilient holder are now vertical instead of being slightly bent or inclined outwardly as in Fig. 2. The canopy may be of any suitable size and shape, and secured thereto is
 55 the bracket 25, the outer end of which carries a lamp socket, not shown.

As will be seen the canopy, both in mounting it and taking it down is held away from

the wall by a sufficient space to prevent it from rubbing and hence all danger of injury to the surface immediately around the finishing plate is avoided. It will also be seen that the resilient holder presses the canopy 65 against the wall in its seated position.

In accordance with the provisions of the patent statutes, I have described the principle of operation of my invention together with the apparatus which I now consider to represent the best embodiment thereof, but I desire to have it understood that the apparatus shown is only illustrative and that the invention may be carried out by other means. 70

What I claim as new and desire to secure by Letters Patent of the United States, is:—

1. In a device of the character described, the combination of a metallic member having supporting means, a holder for a removable canopy comprising a U-shaped resilient piece, the legs of which straddle the member and are secured to the sides thereof, and a second U-shaped piece, the legs of which also straddle the member and are secured thereto and which is provided with means for pressing a canopy support outwardly from a wall thereby flexing the holder until approximately the seating positions of the canopy and its support are reached. 80

2. In a device of the character described, the combination of a metallic member adapted to receive an attachment plug and having supporting means, a pair of U-shaped pieces, the legs of which straddle the member and are secured to the sides thereof, diverging tongues on both of said pieces which act as a guide for a canopy support, one of said pieces being resilient while the other causes said canopy support to deflect the resilient member outwardly as said support is being moved to its final position. 90

3. In a device of the character described, the combination of a metallic member adapted to receive an attachment plug and having supporting means, a pair of U-shaped pieces, the legs of which straddle the member and are secured to the sides thereof, one of said pieces being fixed and the other resilient and movable at one end, diverging tongues on both of said pieces which act as a guide for a canopy support, one of said tongues having a projection near its base which engages said support and presses it and the U-shaped resilient piece outwardly as said support is being moved to its final 105 position. 110

In witness whereof, I have hereunto set my hand this 8th day of November, 1922.

FRANK C. DE REAMER.
